CONTROL MEANS FOR WEFT ENDS IN LOOMS

Richard G. Turner, Worcester, Mass., assignor to Crompton & Knowles Loom Works, Worcester, Mass., a corporation of Massachusetts

Application May 5, 1950, Serial No. 160,167

12 Claims. (Cl. 139—247)

1

This invention relates to improvements in pneumatic thread control systems for weft replenishing looms and more particularly the thread holder and thread collector.

The weft ends of reserve bobbins in the magazine for weft replenishing looms generally lead to some form of thread holder one purpose of which is to hold the thread of a transferred bobbin so that the shuttle may be at least partially threaded on its first flight subsequent to replenishment. In recent years pneumatic thread holders have gone into extensive use more, particularly on multicolor weft replenishing looms. These thread holders are made with an intake mouth and a passage leading to a thread accumulator or collector within which subatmospheric pressures exist. The weft ends from the reserve bobbins enter the mouth and extend through the passage into the collector and become matted with each other to form a mass of yarn which serves as an auxiliary or supplementary holder. When the thread of a transferred bobbin is cut at the cloth selvage it is drawn pneumatically through the holder into the collector where it is confined so that it cannot be whipped into the warp shed by the shuttle.

In the weaving of certain fabrics difficulty is experienced in effecting satisfactory partial threading of the shuttle on the first pick subsequent to replenishment. This difficulty arises more particularly in connection with reverse wind wefts, but it is not necessarily limited to such wefts. In order to take care of this condition I have heretofore proposed, as shown for instance in my co-pending application Serial No. 93,793, filed May 17, 1949, now Patent No. 2,531,177, a mounting for the holder and collector by which these parts are moved rearwardly from their normal position to facilitate threading of the shuttle and are then moved forwardly so that the thread of the freshly transferred bobbin will be drawn toward the fork of the center filling stop motion. When the thread holder and collector move away from the magazine the weft ends are subjected to a tension which may break them, and in order to relieve this tension the aforesaid application shows the holder and collector mounted to swing around a center on their supporting lever so that there will not be an appreciable increase in the length of the weft ends extending from the bobbins to the thread holder.

It is an important object of the present invention to provide the thread collector with a

2

thread retainer roll mounted for rotation in the collector and around which the weft ends are wrapped. When the thread holder and collector move away from the magazine the roll has a reverse turn to pay off a sufficient length of weft ends to compensate for the increase in distance between the thread holder and the magazine. When the holder and collector return toward the magazine a stream of air entering the collector from the thread holder is directed tangentially against the roll or the threads thereon to turn the roll in such direction as to take up slack in the weft ends.

It is another object of the invention to mount the thread roll in the collector so that it can be readily removed from the support on which it turns to enable the weaver to remove an excess accumulation of waste threads from the thread collector.

It is a still further object of the invention to make the roll in the form of a cone which tapers upwardly and mount it for rotation on an upright in the collector which keeps the bottom of the cone above and out of frictional contact with the base of the collector.

It is another object of the invention to provide a simplified mounting for the thread holder and collector unit by means of which it can be swung backwardly and forwardly in the loom at the time of a bobbin transfer, this mounting eliminating some of the structure set forth in the aforesaid copending application.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a side elevation of part of a weft replenishing loom having the invention applied thereto, the lay, shuttle and shuttle box being shown in cross section;

Fig. 2 is a plan view looking in the direction of arrow 2, Fig. 1;

Fig. 3 is a diagrammatic view showing the thread holder in its front and back positions;

Fig. 4 is an enlarged horizontal section on line 4—4, Fig. 1;

Fig. 5 is a vertical section on line 5—5, Fig. 4;

Fig. 6 is a diagrammatic view illustrating the manner in which the stream of air entering the thread collector tends to rotate the thread retainer roll on which the weft ends are wrapped, and

Fig. 7 is an enlarged vertical section on line 1—7, Fig. 5.

Referring more particularly to Figs. 1 and 2, the loom frame 1 has secured thereto a stand 2 on which a reserve bobbin magazine M is pivoted as at 3. The magazine has front and back stacks 4 and 5 of reserve bobbins the weft ends W1 and W2 of which lead from the bobbins in a direction outwardly from the magazine. These weft ends enter a pneumatic thread holder 6 having an intake mouth 7 communicating with an air passage 8 located in a base 9. As shown in Fig. 4 a tube 10, preferably rubber, leads from the right end of passage 8 into a thread collector C.

The magazine M is rocked around its pivot 3 by a train of connections including a rod 11 and a second rod 12 connected to a hook 13 movable into and out of the path of a pin 14 on a normally stationary lever 15 rocked by lever 16 incident to a weft replenishing operation.

The stand 2 supports a transerrer arm 17 movable to insert the lowest bobbin in one or the other of the stacks 4 or 5, depending upon the position of the magazine, into a shuttle S on the lay L. The magazine is intended more particularly for use in a loom having two shuttles which may be called at will, and the magazine will normally be in the position shown in Fig. 1 with the lowest bobbin of one of the stacks under the transerrer arm 17. If the shuttle corresponding to this stack is to be replenished there will be no rocking of the magazine, but if the other shuttle is to be replenished a downward pull of rod 12 when lever 15 is rocked will place the lowest bobbin in the other stack in transfer position. The levers 15 and 16 may be controlled for instance as set forth in my prior Patent No. 2,162,490.

A pneumatic pump 20 connected by hose 21 to the top cover 22 of collector C may be used to create subatmospheric pressures within the collector. Cover 22 may be lifted upon release of a bail 23 for removal of waste threads.

In the operation of the matter thus far described subatmospheric pressures within the collector C cause a stream of air to enter mouth 7, pass out of tube 10, and enter the collector. Any weft ends in this stream will be drawn into the collector and will be held taut. When a bobbin is transferred into a shuttle its weft end will be held by the holder 6 to effect at least partial threading of the shuttle when the latter is picked.

As has already been stated there are some conditions of weaving under which it is desirable to move the thread holder in order to effect proper threading of the shuttle and also correct placement of the thread of the transferred bobbin under the filling fork as the replenished shuttle crosses the lay. These conditions are shown in Fig. 3, where the lay is shown in full lines in picking position and in dotted lines in a position it can occupy while the shuttle is in flight and beyond the filling fork F. If the shuttle has been replenished by a bobbin drawn for instance from the front stack, its thread, identified here at T, will extend from the holder 6 to the shuttle and in order that the latter may be at least partially threaded during its first flight after transfer the thread holder will be in the full line position shown in Fig. 3, that is, a position corresponding to approximately top center position of the lay. When the thread holder is thus related to the shuttle conditions are favorable for at least partial threading of the shuttle.

If the thread holder should remain in the relatively rearward position shown in full lines in Fig. 3 the thread T might be too far behind the filling fork F to support the latter and the loom would be stopped unnecessarily. In order to prevent this stoppage the thread holder is moved forwardly, to the left in Fig. 3, to the dotted line position so that the thread T will be drawn forwardly to a position favorable for cooperation with the filling fork F. These conditions are similar to those described in the aforesaid co-pending application.

In order that the thread holder and collector unit may be mounted for bodily movement to the two positions indicated in Fig. 3 the base 9 is clamped as at 25 to a foot 26 on a lever 27 pivoted as at 28 to a stand designated generally at 29 and bolted to the loom frame as at 30. The lever 27 has an arm or finger 31 connected to one end of a tension spring 32 the other end of which is connected as at 33 to a small stand 34 secured as at 35 to the support 29. Stand 34 has front and back stop screws 36 and 37, respectively, positioned for engagement with the lever 27 to limit its swinging movement about pivot 28.

A flexible connector 40, which may be a cable or cord, has its forward end attached as at 41 to the lever 27 and has the rear end thereof trained around a sheave or pulley 42 rotatable on a stud 43 secured to the support 29. This connector 40 extends downwardly and is attached to a spring 44 the lower end of which is connected to a relatively small lever 45 on a stationary pivot 46 and extending under a pin 47 on lever 15.

The thread holder and collector C and mounting therefor will normally be in the position shown in Fig. 2 with spring 32 acting to hold the lever 27 against forward stop screw 36 so that the thread holder and collector will be forward cor-

responding to the dotted line position of these parts shown in Fig. 3. When a weft replenishing operation occurs pin 47 will be depressed by lever 15 and the cord 40 will be stressed through spring 44, which is strong enough to overpower

spring 32. The lever 27 thereupon swings in a counter-clockwise direction around pivot 28 as viewed in Fig. 2, until it engages the rear stop screw 37. This will locate the thread holder and collector in a position corresponding to the full line position indicated in Fig. 3, and the holder and collector will be in this position at about the time the freshly replenished shuttle is picked. While the shuttle is still in flight and reaches some such position as shown in dotted lines in

Fig. 3, the pin 47 will rise with the rear end of lever 15, whereupon the spring 32 will return the thread holder and collector to their normal forward positions to place the thread of the freshly replenished shuttle favorably for the filling fork F.

By referring to Fig. 3 it will be understood that when the thread holder moves from the dotted line to the full line position the distance between the reserve bobbins of the magazine and the thread holder will be increased and the weft ends, particularly those of the front stack of bobbins, will be placed under additional tension which should be relieved to avoid breakage of the weft ends.

Referring to Figs. 5, 6 and 7, the base 9 has secured thereto and extending upwardly therefrom a rigid upright or support rod 50 which is preferably coaxial with the vertical hollow cylinder 51 of the thread collector C. This rod is fixed

so that it does not rotate but has a thread retainer roll R mounted for rotation on it. Roll R may be made as a hollow conical shell 52 the upper interior part of which has secured therein a wear plug 53 resting on the top of rod 50. The latter holds roll R high enough so that its lower large end will be spaced slightly above the top surface 54 of base 9 within the thread collector. A sheet metal web 55 secured within the roll has an aperture to receive rod 50 and limits swinging motion of the roll on the rod.

As illustrated diagrammatically in Fig. 6 the tube 10 is so disposed that the stream of air issuing from it into the collector is directed tangentially of the roll R and tends to turn the roll in a direction to wind the weft ends on it. This turning of the roll is counter-clockwise as viewed in Fig. 6, and as the weft ends W1 and W2 issue from the tube 10 they will tend to wrap around the outer surface of the roll which may, if desired, be roughened in order to insure better holding of the threads.

When the thread holder is moved rearwardly around axis 28 as already described the increase in distance between the thread holder and the magazine will be compensated for by a reverse rotation of the roll R in a clockwise direction as viewed in Fig. 6 to pay off or unwind an amount of weft ends corresponding more or less to the increase in distance between the magazine and roll. The weft ends W1 and W2 are therefore not subjected to any substantial increase in tension and there is little likelihood that they will break as the lever 27 swings rearwardly. When the thread holder and collector return to their forward position the weft ends W1 and W2 may become momentarily slackened but the existence of subatmospheric pressures within the collector C and also the tendency of air entering the collector to rotate the roll will act quickly to draw the thread slack back into the collector and the weft ends will again become taut and be held above the lay.

It will thus be seen that the thread holder, the thread collector and the base can be rigidly secured as a unit to the lever 27 and that the latter can swing about its pivot 28 without danger of breaking the weft ends; and further that as the result of pneumatic action the roll upon resuming its normal tendency to rotate counter-clockwise as viewed in Fig. 6 will quickly take up any slack in the weft ends resulting from return of the thread holder and collector to their normal forward position.

From the foregoing it will be seen that the invention sets forth means by which the thread holder and thread collector can be secured rigidly to the lever 27 and swing rearwardly with the latter without danger of breaking the weft ends W1 and W2 due to a reverse turning of the roll R in the thread collector on which the weft ends are wrapped. Because of the ability of the roll R to rotate it is not necessary to mount the base 9 for angular movement relatively to the lever 27. It will also be apparent that when a considerable amount of thread accumulates on the roll the cover 22 may be removed and the roll lifted out of the collector so that the waste thread therein can be removed. Furthermore, the roll is supported by the support rod 50 so that its lower end is above the supporting base and does not drag on or frictionally engage it.

Having thus described the invention it will be seen that changes and modifications of the foregoing specific disclosure may be made without

departing from the spirit and scope of the invention.

What is claimed as new is:

1. In control mechanism for the weft ends of reserve bobbins in a weft replenishing loom, a thread holder for said weft ends, a hollow thread collector into which said weft ends extend from the thread holder, means mounting said holder and collector for movement from one position relatively close to the reserve bobbins to another position relatively far from said reserve bobbins, and a rotatable thread retainer within the collector around which the weft ends are wrapped, said retainer rotating in a direction to unwrap a length of said weft ends to compensate for the difference in distance of the two positions of the thread holder and collector from the reserve bobbins when said holder and collector move from said one position thereof to the other position thereof.
2. In control mechanism for the weft ends of reserve bobbins in a weft replenishing loom, a hollow pneumatic thread holder, a thread collector within which subatmospheric pressures exist and the interior of which is in pneumatic communication with the holder, a thread retainer rotatably mounted within the collector, the weft ends extending from the reserve bobbins through the holder into the collector and being wrapped around said retainer, and means mounting the holder and collector for movement in a direction away from the reserve bobbins, said retainer during said movement rotating to pay off a length of weft ends corresponding to the increase in distance of the holder and collector from said reserve bobbins accompanying said movement.
3. In control mechanism for the weft ends of reserve bobbins in a weft replenishing loom, a hollow pneumatic thread holder, a hollow thread collector within which subatmospheric pressures exist and the interior of which is in pneumatic communication with the hollow thread holder, a thread retainer rotatably mounted within the thread collector, the subatmospheric pressures existing within the thread collector causing a stream of air to move through the thread holder into the collector, means directing said stream of air tangentially of said retainer to cause said stream of air to tend to turn said retainer in a given direction, the weft ends extending from the reserve bobbins through the holder into the container and being wrapped around said retainer and being normally taut due to the tendency of said stream of air to rotate the retainer in said given direction, and means mounting said holder and collector for a movement from a position relatively close to said bobbins to another position farther from said bobbins, said retainer during said movement turning in a direction opposite to said given direction to pay off an amount of weft ends to compensate for the increase in distance of said holder from said bobbins during said movement.
4. In control mechanism for the weft ends of reserve bobbins in a weft replenishing loom, a combined pneumatic thread holder and hollow thread collector unit mounted for movement from a position relatively close to the bobbins to a position farther from said bobbins, a roll within the collector, means within the collector mounting the roll for rotation, subatmospheric pressures existing within the collector and said pressures causing a stream of air to move from the holder into the collector, and means direct-

ing said stream tangentially of said roll tending to cause rotation thereof in a given direction, the weft ends extending through the holder into the collector and being wrapped around said roll and being held taut by said roll due to the tendency of the latter to turn in said given direction, said roll turning in a reverse direction when said combined holder and collector unit moves from said one position to said other position thereof to pay off an amount of weft ends to compensate for the increase in distance of the unit from the bobbins when the unit has said movement thereof.

5. In control mechanism for the weft ends of reserve bobbins in a weft replenishing loom, a thread control unit comprising a pneumatic thread holder and a hollow vertical cylindrical thread collector in which subatmospheric pressures exist, said unit having a movement away from the bobbins incident to a weft replenishing operation, an upright within said collector, a thread retainer roll within the collector supported by said upright for rotation thereon, the weft ends extending through the thread holder into the collector and being wrapped around said retainer roll, said subatmospheric pressures causing a stream of air to move from the thread holder into the collector, and means directing said stream tangentially of said retainer roll tending to turn the latter in a direction to keep the weft ends taut, said retainer roll rotating on said upright to pay off a length of weft ends equal substantially to the increase in distance of said thread control unit from the bobbins incident to said movement of the unit away from the bobbins.

6. A pneumatic thread control mechanism for a loom having weft ends extending from reserve bobbins, said mechanism comprising a pneumatic thread holder, a hollow pneumatic thread collector the interior of which is in pneumatic communication with the thread holder, a thread retainer roll within the collector, and means mounting said roll for rotation within the collector.

7. A pneumatic thread control mechanism for the weft ends of reserve bobbins in a weft replenishing loom, said mechanism comprising a pneumatic thread holder, a hollow thread collector the interior of which is in pneumatic communication with the thread holder, and a thread retainer roll rotatably mounted within the thread collector rotatable in one direction to move a thread wrapped therearound from the holder toward the collector and rotatable in the opposite direction to enable the thread to unwrap and move from the thread collector toward the thread holder.

8. In thread control mechanism for the weft ends of reserve bobbins in a weft replenishing loom, a pneumatic thread holder, a hollow cylindrical thread collector the interior of which is in pneumatic communication with the thread holder, an upright within the collector coaxial therewith, and a thread retainer roll mounted on

said upright for rotation thereabout relative to the thread collector.

9. In thread control mechanism for the weft ends of reserve bobbins in a weft replenishing loom, a pneumatic thread holder, a hollow cylindrical thread collector the interior of which is in pneumatic communication at one end thereof with the thread holder, a support within said collector coaxial therewith, and a thread retainer roll rotatable on said support, said support maintaining the end of said roll adjacent to said end of the collector spaced from the latter.

10. In thread control mechanism for the weft ends of reserve bobbins in a weft replenishing loom, a pneumatic thread holder, a hollow cylindrical pneumatic thread collector in pneumatic communication at one end thereof with said holder, a support secured to the collector at said one end thereof, and a thread retainer roll rotatably and removably mounted on said support, said retainer roll being removable from said support by movement in a direction away from said end of the collector.

11. In thread control mechanism for the weft ends of reserve bobbins in a weft replenishing loom, a pneumatic thread holder, a hollow cylindrical thread collector in pneumatic communication at one end thereof with said holder, a support extending coaxially of the collector secured to the latter at said end thereof, and a conical thread retainer roll rotatable on and removable from said support and tapering in a direction away from said end of the collector, said support maintaining the large end of the cone out of engagement with said end of the collector and said retainer roll being removable from the support by movement in a direction away from said end of the collector.

12. In a weft replenishing loom, a reserve bobbin magazine from which weft ends extend, a normally stationary lever having a motion incident to a weft replenishing operation of the loom, and weft end control mechanism operatively interposed between the magazine and lever including a pneumatic thread collector having rotatably mounted therein a roll around which the weft ends are wrapped and including also connections operated by the lever when the latter has said motion moving said collector away from the magazine, whereupon said roll turns to unwrap the weft ends to compensate for the increase in distance between the magazine and collector.
